ANNIVERSARY CAKE CANDLEHOLDER

Albert George McNeill, Philadelphia, Pa., assignee
or to Bachmann Bros., Inc., Philadelphia, Pa.,
a corporation of Pennsylvania

Application May 13, 1946, Serial No. 669,437

4 Claims. (Cl. 41—19)

1

This invention relates to candle holders for cakes and confections for anniversaries, such as birthdays, weddings, and the like, wherein candles are inserted in holding elements on cakes in which the holding elements are designed to equalize the positions of one or a plurality of candles, with the number of periods, such as years, represented by the number of candles.

Various methods have been employed for holding candles on cakes and the like, and whereas individual holders are satisfactory for small numbers, it is difficult to accommodate a sufficient number of individual holders to use enough candles to represent large numbers.

Anniversary cakes are made so that they may readily be decorated to have a pleasing appearance and, therefore, a candle holding device must also have a pleasing design wherein it will also be decorative.

To accomplish this end, the candle holding device of this invention contemplates a decorative device with the notation "Happy Birthday" fancifully displayed thereon. The ring is formed with a continuous circular candle holding groove, and the notation "Happy Birthday" provides means for using a candle holding socket in the center of the ring so that substantially any number of candles may be used in the device with their positions equalized about the center.

A candle holding device of sufficient size to accommodate relatively large numbers of candles must necessarily be formed of elements having considerable thickness, and as weight constitutes an objectionable feature, the device of this invention is made of a plastic or other comparatively light weight material.

The major characteristic of a decorative ornamental device for anniversary cakes and the like is that the device be pleasing to the eye, it being essential that the color of the device be in harmony with the cake or icing thereof.

And to accomplish this end, the ornament is formed of plastic, which may be supplied in various colors which may be made to correspond with the color of the cake or icing.

In various candle holding devices, it has been found difficult to design a holder suitable for holding all numbers, and in particular a device that will hold one candle at one time and two at another. In order to accomplish this purpose, it is necessary to provide ornamental means for providing a candle holding socket exactly in the center and which, at the same time, will hold two candles with the candles on a line passing through the center. This invention, therefore, includes a candle holding device with the notation "Happy

Birthday," the lettering of which makes it possible to provide a candle holding socket exactly at the center without distorting the letters or parts thereof.

The purpose of this invention, therefore, is to provide an ornamental anniversary cake candle holding device which includes a continuous circular groove that provides means for holding the greatest number of candles, in combination with the notation "Happy Birthday," which makes it possible to hold one candle in the center without distortion of the lettering.

To further improve the ornamental features of a candle holding device for anniversary cakes and the like, the device of this invention, which includes a ring, is provided with spaced ornamental sections adapted to improve the appearance and, at the same time, provide covers for hiding holding prongs that may extend from the underside of the device into the cake or the like.

An object of the invention is to provide an ornamental candle holder for cakes and the like, which is suitable for holding one or any number of candles in which the candles may be equalized about the center.

Another object is to provide an appropriate notation on an anniversary cake candle holder which, at the same time, makes it possible to provide a candle holding socket at the center without distortion of the lettering or elements thereof.

Another object is to design and arrange lettering of a suitable notation for candle holding ornaments so that the candles may be held in equalized or natural positions.

Another object is to provide a candle holding ornament for cakes and confections for birthdays, wedding anniversaries and the like in which the ornament may be formed of various colors, and in particular, colors that will blend with the color of the cake or confection or icing thereof.

Another object is to provide a candle holding ornament for birthday and anniversary cakes and the like which may be made relatively large to accommodate comparatively large numbers of candles, and which, at the same time, may be formed of material of relatively light weight.

A further object is to provide a candle holding ornament for cakes for birthdays, anniversaries, and the like which will accommodate one or substantially any number of candles, which is comparatively simple in construction and economical to manufacture.

With these and other objects in view, the invention embodies a comparatively flat ring with a continuous circular groove in the upper surface 55 adapted for holding candles, prongs covered by

ornamental sections at spaced intervals on the ring, a notation such as "Happy Birthday" extending across an open central area of the ring, and a candle holding socket in the said notation positioned in the center of the ring.

For a full and more complete understanding of the invention, reference may be had to the following description and accompanying drawings, wherein:

Figure 1 is a plan view of the ornament.

Figure 2 is a detail showing a section through the candle holding socket at the center of the ornament.

Figure 3 is a cross section through the ring of the ornament showing the continuous candle holding groove and holding prongs.

Figure 4 is a detail illustrating a section of the ring showing the relative positions of the parts.

Figure 5 illustrates the ornament imbedded in the icing of a cake with a plurality of candles therein.

Figure 6 is a similar view showing one candle used in the center of the ornament.

Figure 7 is also a similar view showing two candles used in the ornament on a cake or the like.

Referring now to the drawings wherein like reference characters denote corresponding parts, the ornament of this invention comprises a ring 1 with a continuous circular groove 2 in the upper face thereof.

The under surface of the ring may be smooth or may be provided with prongs 3 which extend downward from grooved sections 4 at spaced intervals around the ring, providing ornamental sections covering the prongs or pins.

The cross sectional shape of the ring may be of the design illustrated in Figure 3 or may be varied, as desired. The ornamental sections 4 may extend outward beyond the periphery of the ring, and over the upper surface, as shown in Figures 1 and 3, or may be incorporated in the ring, or may be omitted, as may be desired.

To provide means for holding a candle in the exact center of the ornament so that the device may be used for the first birthday or anniversary, the notation "Happy Birthday" 5 is provided, which extends across the open inner area of the ring and may be mounted thereon or made integral therewith. In the design shown, a candle socket 6 is formed at the intersection of the vertical member 7 of the letter "P" and the cross member 8 of the letter "T," which makes it possible to locate the socket exactly on the center of the ring 1. It is not desired to limit the invention to the notation "Happy Birthday"; however, it is essential that other notations that may be used have letters, characters or the like that make it possible to provide a socket at the center.

The ornament is illustrated and described as being made of plastic material, and in particular, of a color suitable for harmonizing with cake icing and the like, although it will be understood that any material, preferably of light weight, may be used.

The design and construction of the ornament will readily be understood from the foregoing description. In use, the ornament of this invention may be supplied with a plurality of candles

and may be used either in or on a cake or other confection, and where icing is used, the ornament may be imbedded therein or used thereon. The ornament is obviously centered on the cake and applied with the prongs extending into the upper surface thereof, providing means for holding the ornament in the center. Candles designating one or any number of birthdays or anniversaries may then be inserted in the socket and groove with the candles spaced to be equalized in the groove or about a candle in the center, particularly as illustrated in Figure 5. After use, the candles may be extinguished and the ornament stored for re-use.

15 While a preferred specific embodiment of the invention is hereinbefore set forth, it is to be clearly understood that the invention is not to be limited to the exact construction illustrated and described because various modifications of 20 the details may be provided in putting the invention into practice within the purview of the appended claims.

What is claimed is:

1. In a candle holding ornament for anniversary cakes and the like, the combination, which 25 comprises, a ring having an exposed continuous candle holding groove, and a notation having a single candle holding socket therein, characterized in that the socket is positioned in the center of the ring and groove.

2. In a candle holding ornament for anniversary cakes and the like, the combination, which 30 comprises, a ring having an exposed continuous candle holding groove and holding prongs, and a notation having a single candle holding socket therein, characterized in that the socket is positioned in the center of the ring and groove.

3. In a candle holding ornament for anniversary cakes and the like, the combination, which 35 comprises, a ring having an exposed continuous candle holding groove, and a notation "Happy Birthday," having a single candle holding socket therein, characterized in that the socket is positioned in the center of the ring and groove.

4. In a candle holding ornament for anniversary cakes and the like, the combination, which 40 comprises, a ring having an open continuous candle holding groove and holding prongs, and a notation having a single candle holding socket therein, characterized in that the socket is formed in parts of letters of the notation, and positioned in the center of the ring and groove, and the notation and socket are positioned above the upper surface of the ring.
